(57) **CLAIM**

The ornamental design for a body for automobile, as shown and described.

DESCRIPTION

1. Body for automobile

1.1 : Perspective

1.2 : Perspective view 2

1.3 : Perspective view 3

1.4 : Perspective view 4

1.5 : Perspective view 5

1.6 : Perspective view 6

1.7 : Top

The broken lines depict portions of the body for automobile that form no part of the claimed design; reproduction 1.1 is a rear right top perspective view of the body for automobile; reproduction 1.2 is a rear left top perspective view thereof; reproduction 1.3 is a rear right bottom perspective view thereof; reproduction 1.4 is a rear left bottom perspective view thereof; reproduction 1.5 is a front right top perspective view thereof; reproduction 1.6 is a front left top perspective view thereof; reproduction 1.7 is a top view thereof; this design is for a body for automobile which has a seat, a console, an AI robot, a lamp, and a dashboard which are installed into a vehicle; there are floated displays which are used inside of a vehicle.
